UNITED STATES PATENT OFFICE.

EPPA H. RYON, OF WORCESTER, MASSACHUSETTS, ASSIGNOR TO CROMPTON & KNOWLES LOOM WORKS, A CORPORATION OF MASSACHUSETTS.

SHUTTLE-BOX MOTION FOR LOOMS.

No. 820,018.

Specification of Letters Patent.

Patented May 8, 1906.

Application filed May 8, 1905. Serial No. 259,296.

To all whom it may concern:

Be it known that I, EPPA H. RYON, a citizen of the United States, residing at Worcester, in the county of Worcester and State of Massachusetts, have invented certain new and useful Improvements in Shuttle-Box Motions for Looms, of which the following is a specification.

My invention relates to shuttle-box motion for looms in which two or more change or drop shuttle boxes are used on one or both ends of the loom; and my invention particularly relates to mechanism for operating the shuttle-boxes and to a give-way mechanism connected to the vertically-moving shuttle-box rod carrying the shuttle-boxes and to a balance-spring for the shuttle-boxes.

The object of my invention is to improve upon the shuttle-box-operating mechanism as ordinarily made and the give-way mechanism connected with the shuttle-boxes, and the balance-spring mechanism.

My invention consists in certain novel features of construction of my improvements, as will be hereinafter fully described.

I have only shown in the drawings detached parts of a shuttle-box motion at one end of the loom embodying my improvements, sufficient to enable those skilled in the art to understand the construction and operation thereof.

Referring to the drawings, Figure 1 is a rear view of a box motion at one end of a loom embodying my improvements looking in the direction of arrow *a*, Fig. 2. Fig. 2 is a section on line 2 2, Fig. 1, looking in the direction of arrow *b*, Fig. 1. Fig. 3 is a detached view of the compound box-levers and the give-way mechanism. Fig. 4 is a rear view of the give-way mechanism and the shuttle-box rod looking in the direction of arrow *a*, Fig. 2. The shuttle-box rod is shown in section. Fig. 5 shows the parts of the give-way mechanism shown in Fig. 3 in their open position and the lower end of one part in section. Fig. 6 is a section on line 6 6, Fig. 3, looking in the direction of arrow *c*, same figure. Fig. 7 shows, on an enlarged scale, the pivot-bearing hub portion of a box-lever detached. Fig. 8 is a section on line 8 8, Fig. 7, looking in the direction of arrow *d*, same figure. Fig. 9 is a side view of the remov-

able bearing detached; and Fig. 10 is an end view of the bearing shown in Fig. 9 looking in the direction of arrow *e*, same figure. Figs. 55 3 to 10, inclusive, are shown on an enlarged scale.

In the accompanying drawings, 1 is the loom-frame, 2 is the crank-shaft, 3 the crank-connector to the lay-sword 4, which is pivotally mounted at its lower end in the usual way. The lay-sword 4 carries one end of the lay-beam 5 and hand-rail 6 and also carries the shuttle-box stand or frame 7 for the vertically-moving shuttle-boxes 8—in this instance four in number.

To the loom-frame 1 are secured the arch-stands 9 for supporting the head-frame 10, carrying the well-known Knowles head motion, (shown and described in United States 70 Reissue Letters Patent No. 7,784,) which comprises the pattern surface or chain 11, mounted on the pattern-cylinder 12, over which extends indicator-levers 13, pivoted on the head-frame 10, and each carrying a 75 vibrator gear or crank 14, which is moved into engagement with the lower cylinder-gear 15 or the upper cylinder-gear, (not shown,) all in the usual and well-known way. To each vibrator-gear 14 is attached a 80 vibrator-connector in this instance two connectors 16 on one end of the loom and two connectors 16', extending across the loom to the opposite end thereof.

All of the above parts may be of the usual 85 and well-known construction.

I will now describe my improvements. Each of the two vibrator-connectors 16 is connected with the upper end of a lever 17, pivoted on a stud 18, secured to the stand 9. 90 Each lever 17 is connected at its lower end, through an adjustable link 19, with a gear-segment 20 and 20^a, respectively, which are pivotally mounted on a stud 21. One gear-segment, as 20, meshes with a bevel-gear 22, 95 fast on a shaft 23, mounted on a stand 24, secured to the loom-frame. To the shaft 23 is fast a crank-arm 25, carrying a crank-pin 25', to which is pivotally attached the upper end of a connector 26. The lower end of the connector 26 is pivotally attached to one end of the box-lever 27, which is pivotally mounted on a stud 28 on the end of a second lever 29. The opposite end of the lever 27 is pivotally 100

connected with the lower end of the give-way mechanism 30. (See Fig. 3.) The gear-segment 20^a meshes with a bevel-gear 22^a, fast on a sleeve 23^a, mounted on the 5 shaft 23. Fast on the sleeve 23^a is a crank-arm 25^a, carrying the crank-pin 25^a'. To the crank-pin 25^a' is attached the upper end of a connector 26^a. The lower end of the connector 26^a is pivotally connected to one 10 end of the lever 29, centrally pivoted on a stud 29', carried on a frame or stand 29'', secured to the outer side and lower part of the loom-frame 1 and carrying in this instance a rod 29''', with guide-sheaves 29'''' mounted 15 thereon.

I will now describe the give-way mechanism and the shuttle-box balance-spring. The give-way mechanism 30 comprises the two arms 30' and 30'', which are pivotally connected 20 at their upper ends by a pin 31. (See Fig. 3.) The lower end of one arm, as 30'', is pivotally connected to the front end of the lever 27, as above described, and also has two side extensions 30'''' thereon, between which extends 25 a side extension 30''''' on the arm 30', which side extension has a bevel-shaped forwardly-extending engaging end adapted to be engaged by the foot of the weaver. A coiled expansion-spring 32 is in this instance 30 inclosed within a central opening 32' in the extension 30''''' (see Fig. 6) and is supported at one end in a recess at one end of said opening 32' (see Fig. 5) and bears at its other end against the part 30'', which extends through 35 said opening 32'. (See Fig. 6.) The spring 32 acts to move the engaging end of the side extension 30''''' on the arm 30' outwardly to hold the two arms 30' and 30'' in their normal closed position, as shown in Fig. 3. The 40 two arms 30' and 30'' each have a circular recess 30^a on their inner edge in the usual way to receive in this instance a collar or bushing 33, mounted on a stud 34, which extends out from and is secured to a collar 35, fast on the vertically-moving box-rod 36. The vertically-moving box-rod 36 in this instance is made tubular or hollow and is secured at its upper end to the lower part 8' of the shuttle-boxes 8. Extending within the 45 50 tubular rod 36 is a spiral expansion-spring 37, the upper end of which in this instance bears against a stud 8'', extending down from the boxes 8 within the tubular rod 36. The lower end of the spring 37 bears against the upper end of a vertically-extending rod 39, which extends loosely within the lower end of the tubular rod 36. (See Fig. 4.) The lower end of the rod 39 is fastened to the 55 60 rocker-iron 39'. The spring 37 acts to balance the weight of the shuttle-boxes 8, and being inclosed within the box-rod 36 is concealed and out of the way. By means of the extension 30''''' on the arm 30' of the give-way mechanism the weaver with his foot can 65 move the part 30' to separate it from the

part 30'', as shown in Fig. 5, and allow the shuttle-boxes to be raised or lowered by hand.

I will now describe the construction of the bearing for the pivot-studs of box-levers. In this instance each lever 27 and 29 has a hub portion 27^a and 29^a, respectively, which is recessed to receive the detachable bearing 40 for the pivot-studs 28 and 29. An adjusting screw or bolt 41 extends through a threaded hole in the lower part of each hub and bears at its inner end against the lower surface of the bearing-piece 40. The bearing-piece 40 has projections 40' on its opposite external edges, and in case it is desired by reason of 80 wear on the bearing to make the bearing closer or tighter on the supporting pivot-studs it is only necessary to file off slightly the upper ends of the projections 40'.

It will be understood that the details of 85 construction of my improvements may be varied, if desired, and they may be applied to any shuttle-box motion.

Having thus described my invention, what I claim as new, and desire to secure by Letters Patent, is—

1. In a shuttle-box mechanism of a loom, the combination with the cylinder-gear, the vibrator-gear, and the box-lever, of intermediate connections, comprising a vibrator-connector, a pivoted lever connected therewith, a link connected with said lever, a pivoted gear-segment connected with said link, a bevel-gear meshing with said gear-segment, a rotary shaft or sleeve carrying said bevel-gear, a crank connected with said shaft or sleeve, and a connector therefrom to the box-lever.

2. In a shuttle-box mechanism of a loom, the combination with the cylinder-gear, the 105 vibrator-gear, and the box-lever, of intermediate connections, comprising a vibrator-connector, a pivoted lever connected therewith, an adjustable link connected with said lever, a pivoted gear-segment connected with said 110 link, a bevel-gear meshing with said gear-segment, a rotary shaft or sleeve carrying said bevel-gear, a crank connected with said shaft or sleeve, and a connector therefrom to the box-lever.

3. In a shuttle-box mechanism of a loom, a give-way mechanism for the shuttle-box rod, comprising two arms pivoted together and yieldingly held together, and one of said arms having an extension thereon adapted 120 to be engaged by the foot of the weaver, to move apart the arms and release the shuttle-box rod.

4. In a shuttle-box mechanism of a loom, the combination with the shuttle-boxes, and a tubular vertically-moving rod connected therewith, of an expansion-spring extending within said tubular rod, and having a bearing at its upper end, and a bearing at its lower end against the upper end of a second 130

rod, and said second rod secured at its lower end, and extending loosely within the lower end of the tubular rod.

5. In a shuttle-box mechanism of a loom, the combination with a vertically-moving shuttle-box rod, of a shuttle-box lever, connected with said shuttle-box rod, and having an opening therethrough for a removable bearing for the pivot-support of said lever, and said bearing, and an adjusting bolt or set-screw turning in a threaded hole in said lever, and engaging said bearing.

6. In a shuttle-box mechanism of a loom, the combination with a vertically-moving

shuttle-box rod, of a shuttle-box lever, pivotally connected with said shuttle-box rod, and having an opening therethrough for a removable bearing, and said bearing, having projections thereon which may be reduced in case of looseness of the bearing, and an adjusting bolt or set-screw turning in a threaded hole in said lever, and adapted to engage and adjust said bearing. 15 20
